UNITED STATES PATENT OFFICE.

MELVIN R. SMITH, OF TOLEDO, OHIO.

DESIGN FOR A HOT-WATER BOTTLE.

60,179.

Specification for Design.

Patented Jan. 3, 1922.

Application filed September 10, 1920 Serial No. 409,483. Term of patent 7 years.

To all whom it may concern:

Be it known that I, MELVIN R. SMITH, a citizen of the United States, residing at Toledo, in the county of Lucas and State of Ohio, have invented a new, original, and ornamental Design for a Hot-Water Bottle, of which the following is a specification, reference being had to the accompanying drawing, forming a part thereof.

Figure 1 is a perspective view of the design of hot water bottle taken from one side thereof.

Figure 2 is a similar view from the opposite side.

I claim:—

The ornamental design for a hot water bottle as shown.

MELVIN R. SMITH.
